ILLUMINATING DEVICE

Norman Urban, Parma, Ohio

Application September 20, 1955, Serial No. 535,380

7 Claims. (Cl. 313—113)

The speeds at which powered vehicles travel the highways today makes the illumination from the lights on low beam inadequate for safety and many accidents can be directly traced to this shortcoming of the present headlamps. When the headlamps are positioned on high beam, adequate illumination is furnished for the higher driving speeds, but the approaching traffic is blinded to a great extent by the source of light and glare of the reflectors. This invention is a solution to this problem in that it provides an illuminating device which is equal or superior in illuminating qualities to the present widely used conventional sealed beam headlights on high beam without a blinding glare.

More specifically, the present invention relates to light projecting means comprising in general a reflector and lens so arranged relative to a source of light as to project rays from the latter, and masking means so arranged relative to the source and reflector as to substantially hide them from the normal point of view. The invention is particularly adapted for headlights of automobiles and when so embodied the light source and reflecting surface are substantially concealed from view by an approaching motorist.

It is a primary object of this invention to provide a novel illuminating device having means for directing adequate illumination to a desired area and also having means for minimizing glare.

It is another object of the invention to provide a sealed beam light unit wherein the source of light is positioned between a lens and a reflecting surface and is directed rearwardly against the reflecting surface from whence the light rays are directed to the lens and focused through a small slot or opening formed in the front surface of a hood device which substantially covers the front portion of the sealed beam unit to thereby mask the reflector and light source to minimize glare.

It is a further object of this invention to provide a hood device on the front portion of a sealed beam headlight wherein the front wall of the hood device having the light emitting slot or opening therein is spaced from the outer surface of the headlight lens and openings are provided in the sides, top and bottom of the hood device adjacent the front surface of the lens to permit cooling of the lens and the portions of the hood defining the light emitting slot.

It is another object of this invention to provide an illuminating device which provides adequate illumination for high-speed night driving without giving off an offending glare and therefore eliminates the necessity of providing two beams, i. e., a high beam and a low beam and consequently eliminates the dimmer switch heretofore employed, thus reducing the cost of manufacture.

Some of the objects of the invention having been stated, other objects will appear as the description proceeds, when taken in connection with the accompanying drawings, in which—

Figure 1 is a perspective view of the illuminating device;

2

Figure 2 is a vertical section taken substantially along the line 2—2 in Figure 1;

Figure 3 is a horizontal section taken substantially along the line 3—3 in Figure 2.

5 Referring more specifically to the drawings, the reference numeral 10 broadly indicates an air evacuated sealed lamp shell preferably molded from heat-resistant glass having a concavely curved rear wall portion 10a, when viewed from its inner side, on which is provided

10 a reflective coating serving as a reflector 11. A concavely curved lens portion 12 serves as the front wall of the lamp shell. The lamp shell 10 has a bottom wall 10b which lies in a horizontal plane toward which the top wall 10c of the lamp shell converges to define therebetween at the front the lens 12. The lamp shell 10 has forwardly diverging side walls 10d, 10e to provide the lens 12 with sufficient width to receive all the light rays from the reflector 11. The walls 10a, 10b, 10c, 10d and 10e are all preferably formed from non-reflective light-proof glass.

A U-shaped hood or masking device broadly indicated at 13 preferably formed of a rigid heat-resistant material is bonded to the top and bottom walls 10c, 10b of the lamp shell 10 to act as a mask to substantially hide or conceal the reflector 11 from view. A source of light or filament 14 is provided at a mid-point between the sides of the lamp shell 10 adjacent the lens 12 and has its upper end facing rearwardly for directing the light rays rearwardly to be reflected from the reflector 11.

25 If desired, the light source or filament 14 may be provided with a conventional filament shield for preventing the stray light rays from passing through the lens 12 prior to being reflected and directed by the reflector 11.

The hood 13 is provided with open ends as can be 35 readily observed in Figure 1 and is provided with upper and lower openings or apertures 15 and 16, respectively, for cooling the lens 12 heated by the heat generated by the concentrated light rays. A slot or opening 20 corresponding in length substantially to that of the lens 12 is provided in the front wall of the hood 13

40 through which light rays 24 reflected from the reflector 11 and focused by the lens 12 pass to illuminate the area in front of the illuminating device. The hood 13 is preferably formed from a light-proof and heat-resistant material so as to completely mask all light except the 45 light permitted to be directed through the opening or slot 20 and to prevent the heat generated by the concentrated light rays from damaging the material defining the opening or slot 20. The width of the slot or opening 50 20 is determined by the degree that the lens 12 focuses the light rays 24. However, it will be appreciated that the narrower the slot the greater the masking effect and the slot should be of the least possible width commensurate with adequate illumination.

55 As shown in Figure 2, the positioning of the major portion of the reflector 11 and lens 12 at a higher elevation than the slot 20 directs the light rays 24 outwardly in a horizontal and downward direction from the slot 20. This aids in reducing the glare to an approaching

60 motorist since the illuminating device is normally positioned below the eye level of an approaching motorist. For mounting the illuminating device, for example, on a vehicle, a pair of upper and lower lugs 21, 22 are provided on the hood 13 and a rear lug 23 formed in the medial portion of the rear wall 10a integral with the lamp shell 10 through which suitable means such as bolts are received for firmly securing the illuminating device 65 to the vehicle.

The illuminating device of the present invention may 70 be made of any desired length such as to extend substantially across the front of a vehicle and any desired number of filaments may be used.

There is thus provided an improved illuminating device particularly adapted for automotive use because of its high light intensity and low glare properties but also susceptible of many other uses as occasion may demand, such as air-field lighting.

In the drawings and specification there has been set forth a preferred embodiment of the invention and although specific terms are employed, they are used in a generic and descriptive sense only, and not for purposes of limitation, the scope of the invention being defined in the claims.

I claim:

1. An illuminating device comprising a sealed lamp shell, a concavely-shaped reflector provided in the rear portion of the shell, a lens concavely-shaped throughout its entirety and forming the front portion of the lamp shell, a light source positioned in the lamp shell adjacent the lens, a light-proof hood secured to the front portion of the lamp shell in spaced relation to the lens and having a slot in its foremost portion through which the light rays reflected from the reflector and focused by the lens are directed, and said hood having means for permitting the cooling of the lens from the heat generated by the concentrated light rays.

2. An illuminating device comprising a lamp shell having a substantially flat horizontally positioned bottom wall and an upper wall converging towards the bottom wall, a concavely curved reflector on the inner surface of the rear wall of the lamp shell, a concavely curved lens forming the front wall of the lamp shell, a light source positioned at a mid-point in the bottom wall of the lamp shell and adjacent said lens, a substantially U-shaped light-proof hood secured to the front portion of the lamp shell, said hood having a small slot positioned in a medial portion of the front wall thereof and having openings formed in the top and bottom portions of the hood for permitting air to flow therethrough for cooling the lens from the heat generated by the concentrated light rays.

3. A structure according to claim 2 wherein the major portion of at least the reflector is positioned on a higher level than the slot to direct the light rays from the source of light outwardly from the slot in a horizontal and downward direction.

4. An illuminating device comprising a lamp shell, a reflector on the inner surface of the rear portion of the shell, a lens forming the front wall of the shell, a light source positioned adjacent the lens for generating light rays to be reflected from the reflector, a U-shaped hood secured to the front portion of the lamp shell and having a horizontally positioned slot in a medial portion thereof extending a substantial distance across the width of the device, and the front portion of said U-shaped hood being spaced from the lens and having openings in the top and bottom portions thereof for permitting air to flow therethrough and cool the lens from the heat generated by the concentrated light.

5. An illuminating device comprising a sealed lamp shell having converging upper and lower walls and for-

wardly diverging side walls, a concavely curved lens forming the front wall of the shell, a concavely curved rear wall, a reflector provided on the inner surface of the rear wall, a light source positioned in a medial portion of the lamp shell for directing the light rays rearwardly to the reflector, and light-proof means connected to the outer surface of the lamp shell and extending forwardly thereof and having its foremost portion positioned immediately in front of the lens and in spaced relation thereto, the foremost portion of the light-proof means having a relatively small opening therein for permitting the light rays focused by the lens to pass therethrough while substantially hiding from view the major portions of the lens and reflector whereby the glare caused by the reflector will be substantially eliminated.

6. An illuminating device comprising a lamp shell having a reflector on the inner surface of the rear wall, a concavely curved lens forming the front wall of the lamp shell, a light source positioned in the lamp shell adjacent the lens and directing substantially all of the light rays emanating therefrom rearwardly to the reflector, light-proof means secured to the lamp shell and spaced forwardly from the lens for substantially masking the lens and reflector, said light-proof means having a relatively small opening in its foremost portion for permitting the light rays focused by the lens to be emitted therethrough, and the major portion of the reflector being positioned on a higher level than the opening to direct the light rays from the source of light outwardly from the opening in a horizontal and downward direction.

7. An illuminating device comprising a sealed lamp shell, a concavely curved lens forming the front wall of the shell, a concavely curved rear wall, a reflector provided on the inner surface of the rear wall, a light source positioned in a medial portion of the lamp shell and directing substantially all of the light rays emanating therefrom rearwardly to the reflector, and a light-proof hood connected to the outer surface of the lamp shell and extending forwardly therefrom, the foremost portion of the hood being spaced immediately in front of the lens, said hood having a slot in its foremost portion for permitting the light rays focused by the lens to pass therethrough while substantially hiding from view the major portions of the lens and reflector.
